(57) **CLAIM**

We claim the ornamental design for a housing for an autoinjector, as shown and described.

DESCRIPTION

FIG. 1 is a front perspective view of a housing according to a first embodiment of our new design;

FIG. 2 is a right side view thereof;

FIG. 3 is a front view thereof;

FIG. 4 is a rear view thereof;

FIG. 5 is a left side view thereof;

FIG. 6 is a top plan view thereof;

FIG. 7 is a bottom plan view thereof;

FIG. 8 is a rear perspective view thereof;

FIG. 9 is a front perspective view of a housing according to a second embodiment of our new design which includes a color contrast;

FIG. 10 is a right side view thereof;

FIG. 11 is a front view thereof;

FIG. 12 is a rear view thereof;

FIG. 13 is a left side view thereof;

FIG. 14 is a top plan view thereof;

FIG. 15 is a bottom plan view thereof;

FIG. 16 is a rear perspective view thereof;

FIG. 17 is a front perspective view of a housing according to a third embodiment of our new design which includes a color contrast;

FIG. 18 is a right side view thereof;

FIG. 19 is a front view thereof;

FIG. 20 is a rear view thereof;

FIG. 21 is a left side view thereof;

FIG. 22 is a top plan view thereof;

FIG. 23 is a bottom plan view thereof;

(Continued)

FIG. 24 is an enlarged fragmentary view of the area indicated in dot-dash lines in FIG. 22; and,
FIG. 25 is a rear perspective view thereof.

The portions of the drawings appearing in broken line are for environment only and do not form a part of the claimed design. The shaded portions of FIGS. 9 to 25 of the drawings represent a color contrast.
